United States Patent Office.

G. W. PEABODY, OF EAST HAMPTON, AND O. L. COWLES, OF WESTFIELD.
MASSACHUSETTS.

Letters Patent No. 67,449, dated August 6, 1867.

MACHINE FOR DRESSING AND RENOVATING FEATHERS.

The Schedule referred to in these Letters Patent and making part of the same.

TO ALL WHOM IT MAY CONCERN:

Be it known that we, G. W. PEABODY, of East Hampton, in the county of Hampshire, and Commonwealth of Massachusetts, and O. L. COWLES, of Westfield, in the county of Hampden, in said Commonwealth, have invented a new and useful improvement in Machines for Dressing and Renovating Feathers; and we do hereby declare that the following is a full, clear, and exact description thereof, and of the construction and operation of the same, reference being had to the annexed drawings, making a part of this specification, and to the letters and figures of reference marked thereon, whereof, in plate 1—

Figure 1 is a front elevation of said machine.

Figure 2 is a vertical transverse section through line C—D, fig. 1.

Figure 3 is a vertical transverse section through line E—F, fig. 1.

Figure 4 is a vertical section of steam cylinder; and in plate 2

Figure 5 is an end elevation of said machine.

Figures 6 and 7 respectively, an elevation and a vertical section of the combined valve-key and steam-plug used in said machine; and

Figure 8 is a longitudinal vertical section through the line A—B, fig. 5.

The nature of our invention consists in constructing a machine in which feathers may be cleansed, dressed, and renovated by the action of steam admitted freely among the feathers, and afterwards dried and made fit for use without removing them from the machine, and relates particularly to the method of regulating and distributing the supply of steam, the construction of the valves and means of operating them, and the method of removing the condensed steam from the machine.

The construction of our invention is as follows: A frame of wood, consisting of base H, standards G G G G, and cross-sills a a, supports the feather-holder or receptacle M. This feather-holder is constructed in the form of an octagonal prism, made with closely fitted joints, to prevent the escape of steam as far as possible. Wood side pieces K K, of suitable thickness, and seven in number, are fastened to octagonal ends or heads I I, of the same material. A hinged cover, K', forms one side of the prism, being hinged to an adjoining side at n n, and fastened, when closed, by a small hook and staple at o. This receptacle is from six to eight feet in length, and from two to three feet in diameter, and may be of a cylindrical shape instead of a prism, and, if the latter, may be made in the form of any polygonal prism, any shape approximating to a cylinder being appropriate. Feather-holders of different forms, and of the same general construction as the one herein described, are essential parts of many of the feather-dressing machines now in use. Hollow journals b b, having wide flanges c c at their inner ends, are secured to the heads of the feather-holder by screws passing through the flanges c c into the heads I I. These journals turn in bearings made in the cross-sills a a, and are applied to the feather-holder in line, and so that the latter will revolve evenly in its bearings. A steam cylinder, j, of tin or other sheet metal, and of a diameter of eight inches or more, extends within the feather-holder from end to end, passing through openings in the heads I I, so that the ends of the cylinder meet the flanges c c. Necks S S fastened to the end of the cylinder enter the hollow bearings a short distance and fit closely therein, leaving a clear steam-passage through the hollow bearings into the cylinder. A packing of white lead or other pigment is applied between each end of the cylinder and the flange which comes in contact with it, to make the joint at these points steam-tight. Small drip-pipes p p project from each end of the cylinder through holes in the flanges, and are closed by plugs r r which can be readily removed, for drawing out any water which has accumulated within the steam-cylinder. The feather-holder M being made and set in its bearings in the machine, and the steam-cylinder properly adjusted within the holder, the method of distributing and controlling the supply of steam is next to be described, the object being to admit it freely to the space L between the outside of the steam-cylinder and the inside of the feather-holder for steaming the feathers placed in the space L, or to exclude it entirely from the space L, while the steamed feathers are drying, or after they are removed from the machine. A valve-seat, f, fitted to receive a conical valve, e, has four arms g g g g of equal length, radiating from it at equal distances. These arms are hollow and open into the space e' in the valve-seat. They also pass through the sides j of the cylinder, thus making four steam-channels from the valve-seat into the space L. The outer ends of the arms g g g g project a short distance beyond the surface of the cylinder, to prevent any substance adhering

to the surface of the cylinder from entering the hollow arms. Each arm g is securely fastened by soldering, or otherwise, to the cylinder where it enters it, thus securing the valve-seat rigidly in its place, equidistant from the sides of the cylinder. A conical valve, e , is fitted to the valve-seat f , so that when entered it closes all of the four steam-ways through the arms $g g g g$. For the construction of the valves and valve-seats we prefer to use brass or other metal not easily corroded. In every machine we propose to use two or more of these valve-seats, constructed and applied substantially as described, fitted with conical valves, and fastened at regular intervals along the interior of the cylinder, as shown by black and red lines. If two valve-seats are used there will be eight steam-passages from the interior of the cylinder to the space L . We do not limit ourselves as to the number of these valve-seats to be used in a cylinder, but consider three, affording twelve steam-passages, sufficient for the proper working of the machine. Nor do we limit ourselves to the employment of a valve-seat having radiating arms, but believe the use, in such machines, of a valve-seat having radiating steam-passages, whether the same are in the hollow arms, or formed in a solid disk, of which the valve-seat is the centre, to be new. The conical valve e has a central aperture through its length, and the valve-rod d passes through this aperture, and pins $v v'$ through the valve-rod prevent the valve from sliding on the rod except in the limited space between the pins $v v'$. If only one valve-seat is used, the valve may be pinned rigidly upon the rod, but if more than one is used, we prefer to allow the valve a slight sliding motion upon the valve-rod, and to place a small spiral spring between the pin v and the valve, coiling the same around the valve-rod, thus allowing a little play to the valves, in case any one of the valve-seats should be sprung out of place. The valve-rod d passes through holes in the cross-stays i and i' , set near the ends of the cylinder. To prevent the valve-rod d from turning, a slot (figs. 3 and 4) is made on either side of the hole h in the stay i , and leaves or rectangular pieces of thin metal $X X$, are fastened to opposite sides of the valve-rod. These leaves enter the slots in the stay i , and are long enough to prevent the valve-rod from turning at any point in its motion to and fro in the cylinder. The valve-rod projects into the hollow bearings, and has a screw-thread cut upon it at each end. The last point to be described is the valve-key, which also serves as a steam-plug. This valve-key (figs. 6 and 7) consists of a head, N , stem O , and eye R , and is constructed of iron or other metal. A portion of the head N is turned or necked down at W , forming a groove for the reception of packing. Yarn or other suitable packing is applied at W , to make the head N fit tightly in either of the hollow bearings, the diameter of the head being a little less than the inside diameter of the bearings. A hole, t , large enough to admit the end of the valve-rod, is formed in the end of the head N , and a screw-thread is cut upon the interior, of the proper pitch and size to engage with the screw-thread cut upon either end of the valve-rod. By inserting the valve-key in either of the hollow bearings, the end of the valve-rod will enter the opening t , and upon turning the key the two screw-threads will engage with each other, and the key will have a firm hold of the rod, which latter can then be moved to and from the operator by means of the key, thus giving control of all the valves by one motion of the key. Another use of the key is to serve as a steam-plug to prevent the steam in the cylinder from escaping through the hollow bearing in which the key is inserted.

The operation of our invention is as follows: A boiler for supplying steam is to be used with the machine, the supply pipe from such boiler being attached to one or the other of the hollow bearings $b b$, as is most convenient. The cover K' being opened, the feathers which are to be cleansed and renovated are thrust into the space L , and the cover closed and secured by the hooks and staples. The valves are then opened by means of the valve-key, and the steam passes through the hollow arms g into the space L and among the feathers. The feather-holder M is frequently revolved, to keep the feathers in motion and expose them fully to the action of the steam. When the feathers have been sufficiently steamed the valves are closed by means of the valve-key, and steam is still supplied to the cylinder. The heat then radiates from the cylinder among the moistened feathers, and they are soon dried and renovated. During the process of drying the feather-holder is frequently turned, that the feathers may dry evenly and thoroughly. The steam can be introduced at either end of the machine, as suits the convenience of the operator, the valve-key being then applied at the opposite end.

We are aware that steam has been applied to the dressing of feathers in a revolving feather-holder, and we do not claim the use thereof as novel, nor do we claim the form or construction of the wood feather-holder M , or the steam-cylinder within the same, as all of said devices are of public knowledge and application.

Our invention has reference to the construction of the valve-seats, and their application to the steam-cylinder; to the described method of operating all of said valves together by the action of one valve-rod; to the construction and use of the combined valve-key and steam-plug; and to the arrangement of the drip-pipes shown. We have applied to the valve-seats other valves than conical valves, but prefer the latter, as being simple and durable.

What we therefore claim as our invention, and desire to secure by Letters Patent, is—

1. The use, in combination with the steam-cylinder M , of a feather-dressing machine, of one or more similar valve-seats, each having several steam-passages radiating therefrom and opening into the space L , substantially as described.
2. Operating all the steam-valves in the cylinder M by means of a single valve-rod arranged within the cylinder, substantially as and for the purposes set forth.
3. The combined valve-key and steam-plug, constructed and operating substantially as described.
4. The arrangement of the drip-pipes, placed as described, in combination with the steam-cylinder and hollow flanged bearings, substantially as set forth.

Witness our hands this 30th day of April, A. D. 1867.
